OTHER PUBLICATIONS

Illustration of an ice skate blade bolder and an ice skate blade sold under the trademark "TBLADE".

Primary Examiner — Raphael Barkai

(74) *Attorney, Agent, or Firm* — Wolf, Greenfield & Sacks, P.C.

(57) **CLAIM**

We claim the ornamental design for the ice skate blade, as shown and described.

DESCRIPTION

FIG. 1 is a perspective view of an ice skate blade according to the present design;

FIG. 2 is a right side elevational view of the ice skate blade of FIG. 1;

FIG. 3 is a top plan view of the ice skate blade of FIG. 1;
FIG. 4 is a bottom plan view of the ice skate blade of FIG. 1;
FIG. 5 is a rear elevational view of the ice skate blade of FIG. 1;

FIG. 6 is a front elevational view of the ice skate blade of FIG. 1;

FIG. 7 is a left side elevational view of the ice skate blade of FIG. 1;

FIG. 8 is a perspective view of the ice skate blade of FIG. 1 illustrated with an ice skate blade holder in broken lines;
FIG. 9 is a right side elevational view of the ice skate blade of FIG. 8;

FIG. 10 is a top plan view of the ice skate blade of FIG. 8;
FIG. 11 is a bottom plan view of the ice skate blade of FIG. 8;
FIG. 12 is a left side elevational view of the ice skate blade of FIG. 8;

FIG. 13 is a front elevational view of the ice skate blade of FIG. 8; and,

FIG. 14 is a rear elevational view of the ice skate blade of FIG. 8.

The broken lines are shown for illustrative purposes only and form no part of the claimed design.
